INDEX CARD AND SYSTEM

James H. Rand, North Falmouth, Mass., assignor
to Philrand, Inc., North Falmouth, Mass., a cor-
poration of Massachusetts

Application April 25, 1933, Serial No. 667,810

7 Claims. (Cl. 129—16.7)

This invention relates to an improvement in index arrangements and elements, and particularly to such systems employing a series of overlapped cards or sheets.

5 Many index arrangements afford a series of overlapping sheet elements having laterally projecting supports engageable in channels at either side of a supporting frame or panel. Certain features of the present invention are particularly applicable to index cards of this type.

In accordance with the present invention, the cards or sheets may be provided with holders adapted to engage flanges having their edges spaced inwardly appreciably from the edges of 15 the cards so that the cards cover these flanges. Thus, the supporting or tongue portion of the index card or sheet is narrower than the body portion thereof, and, if desired, tongue portions of a single standardized width may be employed 20 with cards of various widths, the distance between the flange edges in panels of different sizes affording a standardized dimension corresponding to the dimensions of the tongue portions of the cards.

25 This invention further relates to cards or sheets for indexes provided with adjustable signal devices movable into a plurality of adjusted positions. Such a signal device may be associated with the lower edge of each card, this portion of the card being marked with a plurality 30 of symbols, adjoining which the signal may be located to indicate certain conditions in regard to the particular index card. Preferably the lower margin of the card or sheet may be upturned and covered with a transparent sheath, holding the upturned portion in substantially 35 parallel relation to the adjoining lower part of the body portion of the sheet. This upturned portion preferably may be provided with a plurality of 40 openings or recesses to receive the signal, which may be visible not only through the transparent sheath, but above the same. Preferably the signal may be provided in any one of several colors to contrast with the color of the cards and the 45 sheaths. Thus inspection of the visible lower margins of the overlapping index elements or cards permits a quick observation of certain facts in regard to the subject matter indexed by the cards, or the arrangements of words or data 50 included thereon.

In the accompanying drawings:

Fig. 1 is a broken front elevation of an index element formed in accordance with this invention;

Fig. 2 is a broken top view of the same, a portion of a supporting frame also being shown;

Fig. 3 is a section indicated by line 3—3 of Fig. 1;

Fig. 4 is a rear elevation showing a series of 5 index elements of the type illustrated in Fig. 1 arranged in their normal overlapped positions;

Fig. 5 is a perspective view of the signal element;

Fig. 6 is a broken front elevation of an optional form of index element;

Fig. 7 is a broken end or edge elevation of the same;

Fig. 8 is a front elevation of another optional type of index sheet;

Fig. 9 is a broken end or edge elevation of the same; and

Fig. 10 is a broken isometric view of an optional form of index card.

The features of the present invention may be employed either with single index cards or with 20 index elements formed by folding or doubling a sheet back upon itself to afford a front overlapping leaf, and a somewhat longer rear leaf. The latter type of element is illustrated in Figs. 1, 2, and 3, and is designated generally by the 25 numeral 1, including the shorter front leaf 2 and the longer rear leaf 3, connected by an upper return bent fold portion 4.

In accordance with this invention, the element 30 1 may be provided with a support or tongue portion 5 which, as shown in Figs. 1, 2 and 4, may conveniently be in the form of a thin sheet element having portions folded over in engagement with the opposite faces of the upper part of the folded sheet 1. At the front of the index 35 element the sheet metal may be of substantially rectangular form, as shown in Fig. 1, while at the rear thereof its ends are extended to afford tongues 6, the metal being bent outwardly and 40 rearwardly to afford short, laterally inclined connecting portions 8 between the tongues 6 and the adjoining body portion of the member 5. The rear of the member 5 is also extended downwardly to afford a wide depending tongue or 45 flange 9. Preferably the lower corners of this flange taper upwardly to provide inclined edges 10 which are continued in the lower edges of the tongues 6. The sheets 2 and 3, and especially 50 the former, may be weakened, as for example by a perforated line 12 to afford means permitting hinging of the sheets just below the edge of the rectangular front portion of element 5. Thus either the front or rear sheet portion may 55

be swung outwardly from the support and the frame in which the same is received.

To secure the element 5 to the sheet 1, various means may be employed, but I preferably press 5 in the metal of the rear wall of member 5, as by a punching operation, to afford a plurality of indentations 11 which bite into the paper sheet 1. These indentations are arranged so that the next lower element may have its metal supporting 10 part 5 disposed between the tongue 9 and the back of the larger leaf 3 of the superposed element, the upper edge of the element 5 being juxtaposed to the protuberances 11 which may act as stops or abutments, although ordinarily the 15 upper edge of such an element 5 may be spaced slightly below the portions 11 of the superposed element.

Preferably, as shown, the ends of the tongues 6 are spaced inwardly from the edges of the cards 20 or sheets 1. Accordingly this arrangement permits the flanges of the supporting frame to have their edges spaced inwardly appreciably from the edges of the sheets or cards, so that substantial marginal areas of the cards overlap these 25 flanges, and there is little danger of catching the edge of a card upon the edge of a flange. Fig. 2 shows such flanges 14 of a frame 15 supporting an index element 1 in this manner. Furthermore, this arrangement may be employed to 30 permit the use of supporting elements 5 of standardized size to carry cards of various widths, the panels or frames to receive the cards in each case having their flanges spaced at distances corresponding to the spacing of the portions 8 35 of the supporting elements 5, this dimension being independent of the overall width of the panel and the cards received thereby.

In order to facilitate observation of the condition of material which has been written or 40 typed upon the individual index cards, I may provide a signal 20 receivable by the lower marginal portion of the card and adjustable laterally of the same. For this purpose the sheet 3, for example, may have a lower portion folded 45 and turned upwardly, as designated by reference character 3^a, Fig. 3, so that the flange 3^a is in substantial parallelism with the adjoining portion of the leaf 3. Preferably the flange or upturned edge of the leaf 3 may be held in its 50 upturned position by a resilient transparent sheath 21, this sheath being substantially U-shaped, as viewed in cross section, see Fig. 3, and having its longer front leg provided with a downturned flange 22 engaging the edge of the upturned portion 3^a of leaf 3. The opposite leg of the sheath 21 engages the rear face of the leaf 3. Below the downturned flange 22 of the sheath, I preferably provide a series of openings 55 24 in sheet extension 3^a. These openings may 60 be of relatively small diameter so that there may be a large number of the same disposed within the width of a single index element or sheet. If desired, suitable identifying symbols 26 may 65 be disposed upon the portion 3^a of the element adjoining the openings 24. For example, the openings 24 may thus be numbered to correspond to the days of a month.

The signal 20 may be conveniently formed of 70 resilient material, and preferably is provided with a color that contrasts with that of the sheet 1 and the tint of the sheath 21. The general shape of the signal 20 is shown in Figs. 1 and 5, it being provided with a wider upper portion and with a narrower lower extremity 20^a having an inwardly bent end 20^b. The larger upper 75

portion of the signal may be grasped between the thumb and forefinger of the user of the index, and the signal may be lifted out of an opening 24 and thus removed from a card. When it is to be re-inserted in engagement with another opening 24, the sheath 21 may be sprung slightly so that the lower extremity 20^b of the signal is readily inserted in the desired opening 24. The curvature or inclination of the end 20^b of the signal facilitates its re-engagement 10 with an opening in the upturned portion of the element.

Fig. 6 shows an optional arrangement of the holder or support for an index sheet 101, and in this embodiment of the invention the holder or support 105 may be formed of fiber board or pasteboard cut to provide a tongue 109 corresponding to the tongue or flange 9 of Fig. 4, and to provide projecting or laterally extending tongues 106, which, however, are in the plane 20 of the body portion of member 109. Member 109, therefore, is of planar form and may be secured to the upper edge of sheet 101 by a plurality of aligned wire staples 111. These staples cooperate with the tongue 109 and the 25 adjoining upper margin of sheet 101 in affording a recess to receive the upper edge of the next lower index element. For this purpose the upper margin of the element 104 may extend somewhat above the edge of the sheet 101, as 30 indicated by reference character 104^a in Figs. 6 and 7. The staples 111 of one element may thus act as positive stops to engage portion 104^a of an underlying element to prevent the undesired relative movement of the index elements 35 into fully overlapped rather than partially overlapped relationship.

Figs. 8 and 9 show a tongue or supporting element 205 which is connected to and integral with a sheet 201. For this purpose the sheet may 40 have an extension projecting above the edge 198 of its body portion and folded back upon itself to provide a flange 209 of the same general 45 shape as the flange 9, and to provide projecting tongues 206 above and substantially in the plane 50 of the sheet itself. These tongues are preferably spaced from the upper edge of the sheet, and for this purpose the extension thereof is provided with a neck portion 197 defined by inwardly extending slots or recesses 196 adjoining 55 the upper edge of the body portion of the sheet. The tongue portion 205 of the element is retained in its folded shape by wire staples 211, which are disposed above the neck 197. In order to facilitate handling of the index sheet 201, the neck 197 is preferably provided with a scored or slotted line 195, thus to facilitate swinging of the main sheet 201 in relation to the support or tongue 205.

Fig. 10 illustrates an optional embodiment of 60 the invention wherein the body sheet 301 may be provided with a support 305 of the general shape illustrated in Fig. 1, the support 305 preferably being formed however out of sheet material such as thin fiber board, and having its laterally projecting tongues 306 disposed in the plane of its rear wall. In other words, the connecting portions 8 of Figs. 1 and 2 are omitted. This type of support may have a depending flange or tongue 309 and may be held on the 65 upper margin of body sheet 301 by wire staples 311.

It is evident that this invention affords index cards having generally rectangular body portions and supports with laterally projecting tongues 75

terminating within the sides of the body portions, i. e. the supports have substantially less width than the body sheets themselves. Cards of this character may therefore be supported by 5 coplanar retaining flanges which lie over the laterally projecting tongues, while the body sheets provide marginal areas overlapping the outer faces of these retaining flanges. If desired sheets of 10 this type may be provided with retainers on their lower edges to receive colored signals, these signals being adjustable laterally of the respective cards to afford information in regard to the same. If desired symbols may be provided upon the lower parts of the cards or upon the retainers 15 to permit more ready observation of the position of the signal.

I claim:

1. An index card comprising a body sheet of generally rectangular outline, said body sheet 20 having an upturned lower margin, a sheath of resilient transparent material holding said upturned margin in substantially parallel juxtaposition to the adjoining portion of the sheet, said sheath having a flange extending downwardly between the upper edge of said margin and the adjoining body portion of the sheet and having a flange overlapping the opposite face of the sheath, said upturned margin having a series of openings therein, and a signal with a 25 narrow lower portion inserted in one of said openings.

2. An index card comprising a body sheet of generally rectangular outline, a support at the upper edge of the sheet, and a signal-receiving 30 element extending along the lower edge of said sheet, said element providing a series of openings to receive a signal, and a colored signal having a portion inserted in one of said openings.

3. An index card comprising a body sheet of generally rectangular outline, and a retainer of 35 transparent material extending along the lower edge of the body sheet, said body sheet being perforated to afford a series of signal-receiving openings, and a signal of sheet material having a portion inserted in one of said openings and a 40

portion visible through said transparent retainer.

4. An index card comprising a body sheet of generally rectangular outline, said card having a lower portion provided with a row of openings, and a colored index signal having a narrow 5 lower extremity inserted in one of said openings, and a larger portion visible above the opening.

5. An index card comprising a body sheet of generally rectangular outline, said card having a lower portion provided with a row of openings, 10 and a colored index signal having a narrow lower extremity inserted in one of said openings, and a larger portion visible above the opening, and symbols identifying the respective openings at the bottom of the card. 15

6. An index card comprising a body sheet of generally rectangular outline having an upturned lower margin, and a transparent sheath holding 20 said upturned margin in normal parallel juxtaposition to the adjoining portion of the sheet, said sheath being resilient to permit the tilting of said upturned margin away from the adjoining portion of the sheet, said upturned margin having a row of openings therein, and a signal having a narrow lower portion inserted in one 25 of said openings and visible through the sheath, the signal having a portion above the opening and projecting above the sheath.

7. An index card comprising a body sheet of generally rectangular outline having an upturned 30 lower margin, and a transparent sheath holding said upturned margin in normal parallel juxtaposition to the adjoining portion of the sheet, said sheath being resilient to permit the tilting of said upturned margin away from the 35 adjoining portion of the sheet, said upturned margin having a row of openings therein, and a signal having a narrow lower portion inserted in one of said openings and visible through the sheath, the signal having a larger portion above 40 the opening and projecting above the sheath, the lower extremity of said signal being turned at an angle to the adjoining portion thereof to facilitate its insertion in one of said openings.

JAMES H. RAND.
